RENSSELAER W. FRENCH, OF CHICAGO, ILLINOIS, ASSIGNOR, BY MESNE ASSIGNMENTS,
TO DIAMOND RADIO PRODUCTS, OF CHICAGO, ILLINOIS, A COMMON LAW TRUST.

RADIO APPARATUS.

Application filed March 27, 1922. Serial No. 547,304.

To all whom it may concern:

Be it known that I, RENNSSELAER W. FRENCH, a citizen of the United States, and a resident of Chicago, in the county of Cook and State of Illinois, have invented a new and useful Improvement in Radio Apparatus, of which the following is a full, clear, and exact description.

My invention relates to improvements in radio apparatus, and it consists in the combinations, constructions and arrangements herein described and claimed.

An object of my invention is to provide a device of the character described in which positive electrical connections are established between the stator coil and the movable rotor coil.

A further object of my invention is to provide a variometer and vario-coupler having windings in which the capacity effect of the superposed layers is reduced to a minimum.

A further object of my invention is to provide a device of the character described, which permits the rotor to be moved 180° for tuning.

A further object of my invention is to provide a device of the character described, in which the layers of wire on the primary or stator winding are in close registration with the layers of wire upon the rotor, thus increasing the inductive efficiency of the device.

A further object of my invention is to provide a device of the character described, which is extremely simple in construction, which is durable, and which is thoroughly practical for the purpose intended.

Other objects and advantages will appear in the following specification, and the novel features of the invention will be particularly pointed out in the appended claims.

My invention is illustrated in the accompanying drawings, forming part of this application, in which—

Fig. 1 is a side elevation of an embodiment of my invention,

Fig. 2 is a top plan view of the mechanism illustrated in Fig. 1,

Fig. 3 is an end elevation of the mechanism illustrated in Fig. 1,

Fig. 4 is a partial sectional view along the line 4—4 of Fig. 2,

Fig. 5 is a diagrammatic showing of one

layer of the lattice winding used on the 55 stator and rotor coils.

In carrying out my invention, I make use of a stator base member 1 having an arcuate upper surface 2. An annular shell 3 having a lattice wound stator coil 4 wound thereupon is supported upon the base member 1, a portion of the shell 3 being concentric the arcuate surface 2.

The lattice winding employed in the stator coil 4 is more clearly shown in the diagrammatic Fig. 5. This winding consists in a zig-zag winding arranged so that each successive turn is advanced longitudinally on the periphery of the coil 4 approximately one-fourth of an inch, thus producing a lattice-like winding. The next layer of turns will be exactly concentric the first layer, thus reducing the capacity effect between the superposed layers to a minimum.

A rotor 5 consisting of an annular shell 6 of bakelite or other similar insulating compound and a lattice winding 7 carried thereupon is rotatably supported within the stator shell 3 and exactly concentric therewith.

Means for rotatably supporting the rotor 5 is provided in a pair of cross supporting members 8 secured to the inner surface of the rotor shell 6. Stub shafts 9 are secured to the supporting members 8 by means of nuts 10 adapted to hold the supporting members 8 therebetween upon a threaded portion 11 of the shaft 9. The opposite ends 12 of the shafts 9 are arranged to extend through the rotor 5, as shown at 13, the stator shell 3, and the stator winding 4 and extend therebeyond.

The extended portions 12 of the shaft 9 are received in shallow arcuate grooves 14 on the flat upper surfaces 15 of the base 1. Bearing members 16 forming a portion of a single bearing plate 17 are arranged to engage the portions 12 of the shaft 9 to prevent lateral movement of the shaft and to provide a bearing therefor, the plates 17 being secured to the surfaces 15 by means of screws 18.

The plates 17 are each provided with rabbed portions 19 on each side of the opening 20, which opening is formed in the plate 17 because of the spacing apart of the bearing members 16. An annular collar 21 is disposed upon the shaft 9 intermediate the

adjacent sides of the bearing portions 16 and a set screw 22 in each of the collars 21 provides means for fixing the collars 21 against movement relative to the shafts 9.

It will be readily apparent that if either of the shafts 9 is turned, that the rotor 5 will turn therewith as well as the collars 21 on each of the shafts 9, and that in turning, the screws 22 will ultimately move into contact with the rabbeted portions 19 of the plate 17 to stop the rotating of the shafts 9 and the rotor 5. I thus provide an adjustable means (since the collar 12 may be moved longitudinally or turned) for confining the oscillation of the rotor 5 to exactly 180°. This construction is most clearly shown in Fig. 4. The electrical connections of my variometer are as follows: A binding post 23 is supported upon the base 1 and electrically connected by means of a flexible wire 24 to the collar 22 upon one of the shafts 9. The cross support 8 associated with the shaft 9 carrying the collar just mentioned is electrically connected with one terminal of the lattice coil 7 of the rotor 5. The opposite terminal of the coil 7 is electrically connected to the diametrically opposed cross support 8 and the cam 22 carried by the shaft 9 associated with the last named support is electrically connected by means of a flexible wire 25 to one terminal 26 of the stator coil 4. The opposite terminal of the stator coil 4 is electrically connected by means of a flexible wire 27 to the binding post 28. Thus, current admitted to the binding posts 23 and 28 will pass through the rotor and the stator by a series connection.

From the foregoing description of the various parts of the device, the operation thereof may be readily understood. In using my device as a variometer, I connect the binding posts 23 and 28 in precisely the same manner that the ordinary type of variometer

is connected. My device, however, is far more efficient than the ordinary type of variometer and sharper tuning may be accomplished because I have reduced the capacity effect in the stator and rotor windings by the employment of the lattice winding shown in Fig. 5. The device is further efficient inasmuch as the stator winding is disposed so that its individual turns are exactly concentric with corresponding turns upon the rotor 5, thus greatly increasing the inductive efficiency between the adjacent windings. It will be noted, in use the extent of oscillation of the rotor 5 is positively determined by means of the collars 21 and set screws 22. The collars 21 will be

turned relative to one another in such a manner as to limit the oscillation of the rotor to 180° (ordinarily 180° is desirable for efficient tuning).

By shifting the collars 21 laterally upon the shafts 9, I cause the collars to frictionally engage the adjacent sides 29 of the recesses 30 in the base 1 provided to admit the rotation of the collars. This frictional engagement serves as a drag for the rotor and may be varied at will.

In using my device as a vario-coupler, I do not connect the rotor and stator coils in series, but instead, I provide four binding posts, two of which are connected to opposite terminals of the stator winding and the remaining two are connected to the opposite terminals of the rotor winding.

It should be understood that while I have here shown and described a device in which the stator coil 4 is wound upon a shell 3 of an insulating material that the shell 3 may be dispensed with and the stator coil 4 may be self supporting by use of a suitable insulating cement and thus reduce materially the cost of manufacturing the device.

In disposing with the shell 3, which is ordinarily constructed with bakelite or other insulating material, I do away with the capacity effect of the shell itself, since such a shell possesses capacity in itself in the presence of an electric circuit.

I claim:

1. In a device of the character described, an annular lattice wound stator coil of insulated wire, an annular lattice wound rotor coil of insulated wire rotatably mounted within said stator coil and arranged to be moved concentric therewith, each turn of said rotor coil being arranged to exactly underlie its corresponding turn on said stator coil when said coils are concentric with one another.

2. In a device of the character described, having a base and a rotor, a pair of diametrically opposed bearing members mounted on said base, a pair of stub shafts mounted one in each of said bearing members, said rotor being supported on the adjacent ends of said shafts, the collar disposed on each of said shafts and arranged for lateral or rotary adjustment thereon, and set screws disposed for locking said collars against movement of said shaft at will, said set screws being arranged to engage said bearing members to limit the rotation of said rotor, said collars being adapted to frictionally engage said base to drag against the rotation of said rotor.

RENSSELAER W. FRENCH.
